UNITED STATES PATENT OFFICE.

CLARENCE E. DE LUE, OF BOSTON, MASSACHUSETTS.

DESIGN FOR A HAT-PIN.

SPECIFICATION forming part of Design No. 24,677, dated September 17, 1895.

Application filed July 22, 1895. Serial No. 556,834. Term of patent 3½ years.

To all whom it may concern:

Be it known that I, CLARENCE E. DE LUE, a citizen of the United States, residing at Boston, in the county of Suffolk and Commonwealth of Massachusetts, have invented and produced a new and original Design for a Hat-Pin, of which the following is a specification, reference being had to the accompanying drawings, showing a part thereof.

10 Figure 1 is a perspective of a pin, showing my design; Fig. 2, a top or plan view of the same, and Fig. 3 an edge view of the said pin.

The leading feature of my design consists in the diverging curved flat-surfaced members or legs joined by a curved crown portion having a rounded surface.

15 A A are the legs connected by the crown B. The legs A A are diverging, as shown in Figs. 1 and 2, and are also curved, as shown 20 in Fig. 3, said legs also having the flat sides or surfaces a a. The connecting or crown portion B is curved or elliptic in shape and has a rounded surface, which blends or drops to the flat surfaces at the meeting points of 25 the crown and legs. The tips or free ends a'

a' of the legs A A are also shown as rounded, said tips or ends blending into the flat surfaces of the said legs just back of the points.

As already stated, the leading characteristics of the design are the diverging legs 30 curved lengthwise and flat instead of circular, and having the connecting-crown made circular in cross-section, the design thus being distinguished from those hat-pins made with flat essentially parallel legs and a flat 35 crown and those made with round legs and crown, and hence I limit my design to the diverging flat and longitudinally-curved legs and the connecting-crown made circular in cross-section.

40 What I claim is—

The design for hat pins as herein shown and described.

In testimony whereof I have signed my name to this specification in the presence of 45 two subscribing witnesses.

CLARENCE E. DE LUE.

Witnesses:

FREDERICK L. EMERY,
MARGARET A. DUNN.
